(57) **CLAIM**

The ornamental design for a charger box for car, as shown and described.

DESCRIPTION

FIG. 1 is a front view of a charger box for car, showing my new design;

FIG. 2 is a rear view thereof;

FIG. 3 is a left side view thereof;

FIG. 4 is a right side view thereof;

FIG. 5 is a top view thereof;

FIG. 6 is a bottom view thereof;

FIG. 7 is a front perspective view thereof;

FIG. 8 is a partial enlargement of FIG. 7; and,

FIG. 9 is a partial enlargement of FIG. 7.

The broken lines labeling encircling the enlarged portions form no part of the claim.
